FLAME HARDENING CONTROL

John J. Crowe, Westfield, N. J., assignor to Air Reduction Company, Incorporated, New York, N. Y., a corporation of New York

Application January 21, 1941, Serial No. 375,137

7 Claims. (Cl. 148—13)

In flame hardening operations the amount of heat that must be applied to the work is dependent in large measure upon the mass of metal below the surface. With work pieces that are of different thickness at different regions, a progressive flame hardening operation produces non-uniform results unless some provision is made to compensate for the differences in conduction losses at thin and thick sections of the work piece.

One way in which to compensate for the variation in conduction losses as the heating torch progresses across the work is to reduce the heat input where the work piece is thin and increase the heat input at the heavier sections where conduction losses are larger. With heating torches having mat flames and separate gas distributing chambers for the different rows of flames, some of the flames can be turned off to reduce the heating effectiveness of the torch, but with single-row torches it is not practical to extinguish any of the flames because that makes the heating uneven transversely of the work piece.

It is an object of this invention to provide an improved and simplified method and apparatus for controlling a heating torch used for flame hardening, and for varying the heating effectiveness of a single row of flames without extinguishing any of the flames and without changing the distance from the torch to the work.

The torches used for flame hardening have distributing chambers from which a mixture of oxygen and fuel gas is discharged through jet orifices in the face of the torch tip. The velocity of the combustible mixture as it comes from the orifices should be kept higher than the rate of flame propagation to prevent the flames from entering the torch. It has not been considered feasible, therefore, to obtain any substantial reduction in the rate of heating by reducing the flow of oxygen and fuel gas to the flames.

With this invention the supply of combustible mixture is reduced without necessarily reducing the velocity of discharge of the mixture from the orifices. The invention supplies to the torch an inert gas, that is, a gas that will not react with either the oxygen or the fuel gas. This inert gas is a diluent in the combustible mixture and reduces the heating to some extent by absorbing sensible heat from the combustion reaction. The principal function of the diluent gas, however, is to increase the volume of the gas mixture without increasing its heating value. Thus with the same velocity of gas discharge from the jet orifices of the torch, the fuel and oxygen are pro-

portionately less, the greater the dilution of the mixture with inert gas.

Another object of the invention is to provide an improved automatic control for changing the heating effectiveness of a torch during a flame hardening operation.

Other objects, features and advantages of the invention will appear or be pointed out as the specification proceeds.

In the accompanying drawing, forming part hereof:

Fig. 1 is a diagrammatic side elevation showing apparatus for flame hardening a work piece in accordance with this invention.

Fig. 2 is an enlarged sectional view taken on the line 2—2 of Fig. 1.

A self-propelled torch carriage 10 has wheels 11 that run on a track 12, or other suitable support. There is a post 13 at the forward end of the carriage for holding the supporting brackets of the heating torch and quenching head. The front wheels 11 of the carriage are driven by a motor 15 equipped with governor 16 that can be adjusted to regulate the speed at which the carriage moves along the track.

An arm 18 has a split clamp 19 at one end vertically adjustable on the post 13. Another split clamp 20 at the other end of the arm 18 holds a stud 21 that comprises the supporting end of a bracket 22. A heating torch 23 and a quenching head 24 are connected to the bracket 22 and supported by the bracket in working relation to the top face of a work piece 26 located along one side of the track 12.

The heating torch 23 is shown in section in Fig. 2 and includes a mixer 28 that screws into the top of a tip block 29. The mixer 28 is constructed to mix three gases, but the invention can use, as an equivalent construction, a conventional torch mixer and a supply conduit for introducing the diluent into the oxy-fuel gas stream somewhere between the mixer and the tip. There is a distributing chamber 30 within the tip block 29 and a single row of jet passages 31 lead from the distributing chamber 30 and open through the bottom face of the torch.

The mixer 28 has two conduits 32 and 33 that come together at equal acute angles to the axis of a common mixing passage 34. Fuel gas is supplied to the conduit 32 from tubing 35, and oxygen is supplied to the conduit 33 from tubing 36 connected with the mixer. The diluent gas is supplied to the mixer through tubing 37 that connects with a passage or conduit 38 in the mixer.

This conduit 38 meets the mixing passage 34 in a discharge passage 39. The passages 38 and 34 preferably make equal angles with the axis of the discharge passage 39.

The fuel gas and oxygen are supplied to the conduits 32 and 33 and preferably at pressures that cause the gases to mix in the most desirable ratio for combustion in the heating flames. When gas is supplied through the passage 38, the pressure of the diluent gas reduces the flow of oxy-fuel gas mixture from the discharge passage 39. In the operation of the torch, therefore, the oxygen and fuel gas supply pressures can be left unchanged, and by varying the supply of diluent gas the amount of oxygen and fuel gas supplied to the tip can be varied over a wide range.

The variation in the supply of diluent gas makes little or no change in the gas pressure in the distributing chamber 30. The velocity of gas flow through the jet passages 31 is, therefore, substantially constant even though the amount of oxygen and fuel gas supplied to the flames varies over a wide range. A constant supply of fluid flows to the quenching head 24 through a hose 40.

Nitrogen can be used as the diluent gas. Air is also suitable even though the air is about 20% oxygen, this addition to the oxygen supply is ordinarily not objectionable. When air is used as the diluent gas, it is the inert constituents of the air that serve as the diluent.

A valve 41 commands the tubing 37 and conduit 38 of the mixer. The valve 41 is located in a valve casing 42 connected with the side of the carriage 10. Gas is supplied to the valve casing 42 through a hose 43. The valve 41 has a bias toward closed position, being preferably urged toward closed position by a spring 44. When the valve 41 is closed, no gas can flow from the hose 43 to the tubing 37.

The valve 41 has a stem that projects through the upper wall of the valve casing, and a bell crank 46 has a forward arm that contacts with the valve stem and displaces the stem to open the valve when the bell crank is rocked counter-clockwise. The bell crank 46 is connected to the side of the carriage 10 by a pivot 47 and the rearward arm of the bell crank 46 projects downward and outward from the side of the carriage and has a cam-follower roller 48 at its lower end.

The roller 48 operates over a cam 50 that is preferably held in place by screws 51 that extend into the side of the track 12 but hold the cam 50 at some distance from the side of the track so that the cam-follower 48 and the lower end of the bell crank 46 do not scrape the side of the track.

The cam 50 is designed for the work piece 26 and has a low mid-portion that causes the bell crank 46 to rock clockwise and close the valve 41 so that there is no diluent gas supplied to the tubing 37 during the time that the torch 23 is traveling across the thick section of the work piece where conduction losses are large.

As the torch 23 passes beyond the heavy section and comes over the thin portion of the work piece beyond the web, there is a rise in the cam 50 that shifts the bell crank counter-clockwise and opens the valve 41 part way. As the torch approaches the end of the work piece where there is a decreasing mass of metal ahead of the flame system, there is a progressive rise in the cam 50 for opening the valve 41 wider to increase

the supply of diluent gas to a maximum at the end of the work piece. The cam 50 ends at a point corresponding with the arrival of the torch 23 at the end of the work piece so that the roller 48 runs off the end of the cam 50 and causes the valve 41 to close as soon as the torch moves beyond the end of the work piece. An abutment 52 extending from the track 12 is used to position the work piece 26 with respect to the cam 50.

Changes and modifications can be made in the illustrated embodiment. Terms of orientation are, of course, relative, and some features of the invention can be used without others.

I claim:

1. In a flame hardening operation in which a heating torch is moved progressively across a work piece, the method of controlling the heat which comprises supplying an oxy-fuel gas mixture to the torch for the heating flames, diluting the oxy-fuel gas mixture with an inert gas to reduce the heat generated by the torch, and while said torch is moving progressively across the work-piece, varying the dilution inversely to the changes in the conduction losses from the region of the surface over which the torch is operating.

2. In a flame hardening operation in which a heating torch is moved progressively across a work piece by a carriage that moves along a support, the method of controlling the heat generated by the torch as it travels over regions of the surface from which heat is lost by conduction at different rates, which method comprises supplying an oxy-fuel gas mixture to the torch for the heating flames, diluting the combustible mixture with inert gas to reduce the rate of discharge from the torch of oxygen and fuel gas without proportionately reducing their velocity of discharge, and varying the dilution in response to displacement of the carriage along its support.

3. The method of controlling the heat in a flame hardening operation performed by one or more heating flames that move progressively over the surface of a work-piece to be hardened, which method comprises reducing the heat generated, while leaving the number of flames unchanged, by diluting with an inert gas the mixture supplied to the one or more flames, and changing the dilution during the flame hardening operation in accordance with changes in the heat required by the work piece.

4. Flame hardening apparatus comprising a heating torch having a tip and a mixer in which oxygen and fuel gas are brought together and supplied to the tip, a conduit through which a diluent gas is supplied to the torch, a valve commanding said conduit, and automatic means for operating the valve in response to displacement of the torch to change the supply of diluent gas during a flame hardening operation.

5. Flame hardening apparatus comprising a carriage movable along a support, a bracket on the carriage, a torch supported by the bracket in position to move across the surface of a work piece as the carriage moves along said support, a mixer in which oxygen and fuel gas are brought together and supplied to the tip, a conduit through which a diluent gas is supplied to the torch, a valve on the carriage commanding said conduit, and automatic control means for operating the valve in response to displacement of the carriage lengthwise of the track.

6. Flame hardening apparatus comprising a wheeled carriage, a track on which the carriage runs, a governor-controlled motor on the carriage

for causing the carriage to move along the track at a predetermined speed, a heating torch and a quenching head, a bracket on the torch for supporting the heating torch and quenching head above the surface of a work piece, means for supplying oxygen and fuel gas to the torch, means for supplying a constant quantity of quenching fluid to said quenching head, a conduit through which an inert diluent gas is supplied to the torch, a normally-closed valve on the carriage 10 for controlling the supply of diluent gas to said conduit, a cam adjacent the track and extending in the direction of the track, a cam-follower extending from the carriage and contacting with the cam as the carriage moves along the track, 15

and valve-operating means on the carriage connected to the cam-follower.

7. Flame hardening apparatus comprising a heating torch having a tip and a mixer having a mixing passage, an oxygen supply conduit and a fuel gas supply conduit that come together at equal acute angles to the axis of the mixing passage into which said conduits open, another conduit for supplying a diluent gas to the oxy-fuel gas mixture, said other conduit and the mixing passage converging at equal acute angles to a discharge passage through which the mixture of oxygen, fuel gas, and diluent gas flows to a distributing chamber of the tip.

JOHN J. CROWE.
